US00D863236S

(12) **United States Design Patent** (10) **Patent No.:** **US D863,236 S**
Plaja Miro et al. (45) **Date of Patent:** **** Oct. 15, 2019**

(54) **ELECTRICAL SWITCH**(71) Applicant: **SIMON, S.A.U.**, Barcelona (ES)(72) Inventors: **Salvi Plaja Miro**, Barcelona (ES);
Adria Rique Rebull, Barcelona (ES);
Clara Batiste Mayas, Barcelona (ES);
Marta Portillo Lainez, Barcelona (ES)(73) Assignee: **SIMON, S.A.U.**, Barcelona (ES)(**) Term: **15 Years**(21) Appl. No.: **29/586,398**(22) Filed: **Dec. 2, 2016**(30) **Foreign Application Priority Data**

Jun. 2, 2016 (WO) DM/092499

(51) **LOC (12) Cl.** ..... **13-03**(52) **U.S. Cl.**USPC ..... **D13/169**(58) **Field of Classification Search**

(Continued)

Primary Examiner — Selina Sikder(74) *Attorney, Agent, or Firm* — Lucas & Mercanti, LLP(57) **CLAIM**

The ornamental design for electrical switch, as shown and described.

DESCRIPTION

FIG. 1 is a top view of the electrical switch showing my new design;

(Continued)

FIG. 2 is a side view thereof;
FIG. 3 is a front perspective thereof; and,
FIG. 4 is a front elevation view.

1 Claim, 1 Drawing Sheet
